UNITED STATES PATENT OFFICE

136,133

DESIGN FOR AN EXTERNAL ENERGIZER FOR INTERNAL COMBUSTION ENGINE STARTERS

David J. Conant, Cleveland Heights, Ohio, assignor to Jack & Heintz Research Corporation, Bedford, Ohio, a corporation of Ohio

Application May 14, 1943, Serial No. 110,206

Term of patent 14 years

To all whom it may concern:

Be it known that I, David J. Conant, a citizen of the United States, residing at Cleveland Heights, in the county of Cuyahoga and State of Ohio, have invented a new, original, and ornamental Design for an External Energizer for Internal Combustion Engine Starters, of which the following is a specification, reference being had to the accompanying drawings, forming part thereof, wherein:

Figure 1 is a side elevational view of an external energizer for internal combustion engine starters showing my new design portions being broken away for convenience of illustration;

Figure 2 is a side elevational view taken at right angles to Figure 1;

Figure 3 is an end elevational view looking at the handle end; and

Figure 4 is an end elevational view of the other end thereof.

Figure 5 is a side elevational view of the complete device.

I claim:

The ornamental design for an external energizer for internal combustion engine starters, substantially as shown.

DAVID J. CONANT.
